UNITED STATES PATENT OFFICE.

HOWARD R. McBRIDE, OF NEW ORLEANS, LOUISIANA, ASSIGNOR TO NATIONAL FRUIT FLAVOR COMPANY, OF NEW ORLEANS, LOUISIANA, A CORPORATION OF LOUISIANA.

DESIGN FOR A BOTTLE.

Application filed October 10, 1927. Serial No. 23,696. Term of patent 14 years.

To all whom it may concern:

Be it known that I, HOWARD R. McBRIDE, a citizen of the United States, residing at New Orleans, parish of Orleans, State of Louisiana, have invented a new, original, and ornamental Design for a Bottle, of which the following is a specification, reference being had to the accompanying drawing, forming a part thereof.

I claim:

The ornamental design for a bottle substantially as shown.

HOWARD R. McBRIDE.
